UNITED STATES PATENT OFFICE.

EDGAR ARNOLD PALLISTER, OF LEEDS, COUNTY OF YORK, ENGLAND.

MACHINE FOR FOLDING AND EYELETING LABELS.

SPECIFICATION forming part of Letters Patent No. 323,067, dated July 28, 1885.

Application filed November 22, 1883. (No model.) Patented in England October 21, 1880, No. 4,299.

To all whom it may concern:

Be it known that I, EDGAR ARNOLD PALLISTER, a subject of the Queen of Great Britain and Ireland, residing at Leeds, in the county of York, England, have invented certain new and useful Improvements in Machinery for Folding and Eyeleting Labels, of which the following is a specification.

Letters Patent for this invention were granted to me in Great Britain on October 21, 1880, and are numbered 4,299.

My invention relates to the label-carrier, to the templets for giving the folds to the label, to the mechanism for punching and eyeleting the label, and to the mechanism for actuating the various parts, all as hereinafter detailed.

In the drawings, Figure 1 is a side elevation of the machine. Fig. 2 is a front elevation, and Fig. 3 is a rear elevation, of the machine. Fig. 4 is a vertical section of the upper part of the machine at the line A B of Fig. 2. Fig. 5 represents the label after the side folds have been made, and Fig. 6 shows the label after the end fold has been made. Fig. 7 is a section of the female templet, the plate or table for supporting the label, and the pusher. Fig. 8 is a plan of the parts shown in Fig. 7 below the line y y. Fig. 9 is a plan view of the male templet, label-carrier, and swinging arm. Fig. 10 is a front elevation of the swinging arm and its parts and the means for actuating them. Fig. 11 is a side elevation of the parts shown in Fig. 10. Fig. 12 is a perspective view of the male and female templets and of part of the plate over which the label is carried. This figure illustrates how the side folds are given to the label. Fig. 13 is a sectional view showing the same parts represented in Fig. 7, but with the pusher just commencing to push the label between the two plates that form the end fold to the label.

a represents the frame of the machine, and b are bearings thereon for the axis b' of the forked arm e. This arm receives a swinging movement through the cam g, lever w, link i, and lever k, the latter being keyed to the axis b' of the arm e. The label-carrier is mounted upon the arm e, and is made with a base-piece, h, fitted to slide upon the arm e, and adjusted thereon by the screw h' to accommodate the length of label. The lower end of the label

rests upon the stop h', and h² h² are flanged carriers which support the sides of the label.

e is the male templet, secured to a slide, d, that moves in a mortise in the arm c, and the upper end of this templet is of triangular or $\wedge$ shape. The slide d and templet e receive a vertical movement at the proper time by the cam n, bent lever m, and link l. The lever m is slotted for the bolt that connects the link l to m; hence by varying the position of the bolt in said slot the movement given to the slide d may be varied to suit the label operated upon. The cams n and g are upon a shaft, g³, that receives its motion from the driving-shaft o and gearing p. The female templet f is a plate secured to the cross-bar f' of the frame f² f² f³. This plate f has a notch therein, of the same shape as the triangular end of the male templet e, but slightly larger, and the plate f is recessed to leave a space between the plate f and the bar f', to allow for the passage of the templet e and the partly-folded label.

The operation of the parts thus far described is as follows: The label l' is placed between the carriers h², with its lower end resting against the stop h', as illustrated by the dotted lines in Fig. 15, and full lines in Fig. 14. The arm c is now swung toward the frame of the machine by the cam g and connections, and the male templet e and upper part of the label are carried into the female templet f. As the templet e passes by the edges of the notch in f the upper corners of the label are bent over against the edges of e, forming the side folds of the label, as represented in Fig. 5. The slide d is now actuated by the cam n, bent lever m, and rod l, and the male templet e is raised vertically within the female templet f, carrying the label with it until the top of the label is above the opening between the two plates t v, hereinafter described. The slide d is now drawn down, bringing with it the male templet, and leaving the label to be acted upon by the pusher x. The pusher x is a thin metal plate at the upper ends of the levers w, which levers swing upon the shaft y, and are actuated by the cam g. The plate v is made in two parts, connected together by the screw v', and secured to the cross-bar f'. The arm t is over the central part of

the plate v , and is secured to the cross-bar a' of the frame. There is space between the plate v and arm t sufficient for the passage of the pusher and label. The vertical bars f^2 5 f^2 , that support the cross-bar f' , are bent at their lower ends and attached to the frames a , and they are at a sufficient distance from the frames a to leave room for the movements of the levers w , next described. When the male 10 templet e has been drawn down and left the label l' with its upper end projecting from the female templet f , as aforesaid, the upper ends of the levers w and the pusher x are outside the back of the machine, and are moving to- 15 ward the label. As the pusher advances it presses against the projecting end of the label, and said end of the label is turned back upon the pusher x by the angle 25 of the cross-bar a' as the pusher carries forward the label be- 20 tween t and v , as illustrated in Fig. 13, and this gives the end fold to the label shown at s in Fig. 6. The pusher x moves the label forward upon the plate v , and beneath a spring, 1, to the position shown in Fig. 4, where the 25 punching and eyeleting operations are performed. The pusher x is drawn back after the label has been brought to position as aforesaid, and the spring 1 holds the label in place while the pusher is being drawn back, and al- 30 so while the punching and eyeleting are being performed.

The operation of punching is effected by the 35 punch 2, mounted on the sliding piece 3, and the die 4, which is carried on the swing-frame 5. The required movement is given to the 40 punch 2 from the cam 6 or its equivalent through connecting-rod 7 and lever 8. After the punching operation, and as soon as the punch 2 is withdrawn, the swing-frame 5, carrying the die 4, is moved out of the way for the eyeleting operation, and for this purpose I employ the slot-plate 9, which forms the 45 lower end of the swing-frame 5, which is actuated as hereinafter described.

45 For the eyeleting operation the vertical rod 10 is provided, into the top of which is fitted a pin, 11, which projects therefrom (and which is retained in the projecting position by means of a spiral spring, 11'), in the upper end of the 50 rod 10) to receive the eyelet from the spout or conductor 12 of the feeding-box 13. Having received the eyelet, and the hole in the label having been punched, a vertical movement is imparted to the rod 10 by the cam 14, which forces the eyelet through the hole in the 55 label. The punch 2 is brought down again and passes within the eyelet, causing the pin 11 to retire into the end of the rod 10. The rod 10 carries a projecting pin and runner, 15, 60 in its lower half, which engage in the slot in slotted plate 9. The vertical movement of the rod 10 and runner 15 thus causes the swing-frame 5 to tilt to one side, moving the die 4 out of the way for the eyeleting operation. 65 The enlarged part of the punch 2 and the end of the vertical rod 10 are brought together, thereby clinching the eyelet in the label. This

being done, the punch 2 and the vertical rod 10 retire clear of the eyelet. After this operation the levers or arms w , carrying the pusher 70 x , continue to move back in the direction shown by the arrow, Fig. 4, and carry with them the loose hanging pieces 45 to the rear end of the label. When a forward movement is given to the arms w and pusher x , as before 75 described, the hanging pieces 45 push the eyeleted label forward, whence it may be allowed to drop into a convenient receptacle. The feed-box 13 and spout or conductor 12 are supported by two pivoted arms, 16, upon a 80 stationary plate that projects laterally from the frame a . One of the arms 16 is made as one end of a bent lever, and to the other end of said lever at 255 there is a pivoted link that is connected at its lower end with the slotted 85 plate 9. The parts are so proportioned that as the bar 10 and pin 11 are moved up the conductor 12 is swung so that the last eyelet is taken upon the end of the pin 11, and then the conductor 12 is drawn back out of the 90 way of the further movement of the pin as it carries the eyelet up into the label or tag.

When the machine is required to be worked by manual labor, motion is imparted from the treadle 17 to the crank 18 by means of a connecting-rod; but when it is driven by motive power motion is transmitted to the driving-shaft o from the fast pulley 19. 95

I claim as my invention—

1. The combination, with the swinging arm 100 c , adjustable label-carrier, slide d , and male templet secured to said slide, of the stationary female templet f , and means for actuating the swinging arm and slide, substantially as set forth. 105

2. The swinging arm c , adjustable label-carrier, levers k and w , link i , and cam g , in combination with the slide d , templet e , connecting-rod l , bent lever m , cam n , and means for rotating the cams, substantially as and for the 110 purposes set forth.

3. The combination, with the swinging arm c , label-carrier, slide d , male templet e , and female templet f , of the plates $t v$, pusher x , levers w , and means, substantially as specified, 115 for actuating the arm, slide, and levers, substantially as set forth.

4. In a machine for folding and eyeleting labels, the combination of a swinging arm, a label-carrier, a slide mounted on said arm, a 120 male templet secured to said slide and having a triangular upper end, a female templet having an opening in its face corresponding to the shape of the end of the male templet, and means for swinging the arm and carrying 125 the male templet and label into the female templet, substantially as set forth.

5. The combination, with the plates $t v$ and spring 1, secured to said plates, of the levers w , fingers 45, hanging loosely from said levers, 130 the pusher x , and means for actuating said levers w , substantially as and for the purposes set forth.

6. The combination, with the swinging arm

c, of the label-carrier consisting of the base-piece *h* and adjusting-screw *h*³, the stop *h'*, and plates *h*², substantially as and for the purposes set forth.

5 7. In combination with the means for folding and holding the label, the slide 3 and punch 2, and means for actuating the slide, the swinging frame 5, having a cam-slot therein, the die 4, carried by said frame, the vertical

sliding bar 10, the spring-pin 11 at the top of 10 said bar 10, the runner 15, entering the cam-slot in frame 5, and means for actuating the bar 10 and for supplying eyelets to the pin 11, substantially as set forth.

EDGAR ARNOLD PALLISTER.
